DRILL FEEDING MECHANISM

John L. Reilly, Claremont, N. H., assignor to Sullivan Machinery Company, a corporation of Massachusetts

Application April 30, 1934, Serial No. 723,069

2 Claims. (Cl. 255—51)

This invention relates to feeding mechanism, and more particularly to improvements in the feeding mechanism of a rock drill of the mounted hammer type.

5 An object of this invention is to provide an improved rock drill feeding mechanism. Another object is to provide an improved feeding mechanism for a hammer type rock drill, wherein the drill is automatically fed by the vibrative action 10 set up within the drill by the hammer motor. Another object is to provide an improved automatic rock drill feeding mechanism controlled by the vibrative action set up within the drill during the drilling operation and having associated 15 therewith improved recoil resistance means. Yet another object is to provide an improved rock drill feeding mechanism wherein a feeding drum and cooperating cable are employed for effecting drill feed, the drum having associated therewith improved recoil resistance means in the form 20 of an intermittent grip device whereby drum rotation is controlled automatically by the degree of penetration of the drill steel into the work. Still another object is to provide, in a feeding 25 mechanism of the above character, improved means for regulating the rate of feed. These and other objects will, however, subsequently more fully appear.

In the accompanying drawing, there is shown, 30 for purposes of illustration, one form which the invention may assume in practice.

In this drawing,—

Fig. 1 is a side elevational view of a rock drilling mechanism having associated therewith an 35 illustrative form of the improved automatic drill feeding mechanism.

Fig. 2 is a transverse vertical sectional view taken on line 2—2 of Fig. 1.

Fig. 3 is a cross sectional view taken on line 40 3—3 of Fig. 2.

Fig. 4 is a detail sectional view, taken on line 45 4—4 of Fig. 2, showing the drum reverse lock.

In this illustrative embodiment of the invention the improved automatic feeding mechanism, generally designated 1, is shown embodied in a rock drilling mechanism of the wagon-mounted tower type, although it will be evident that the improved feeding mechanism may be associated with drilling mechanisms of various 50 other types.

The drilling mechanism shown comprises a wheeled truck frame 2 mounted on wheels 3; and carried by this truck frame is a vertical guide frame or tower 4, suitably braced with respect to the truck frame by means of brace rods 5. The

guide frame or tower 4 is provided with vertical guideways and mounted on this guide frame for movement along its guideways is a frame 6 supporting a rock drill 7 herein of the pressure fluid actuated, reciprocating hammer piston impact type, having an impact motor for percussively actuating a drill steel 8. This rock drill is of a well known design, and as the particular construction of the rock drill does not enter into this invention, further illustration and description of 10 the same are considered unnecessary other than to state that as the hammer piston reciprocates under the action of pressure fluid, a vibrative action is set up within the drill in a direction longitudinally of the drill guideways, as is inherent in such drills.

In accordance with the present invention, means are provided to effect feeding of the rock drill in a direction longitudinally of its guiding frame by the jars or shocks to which the drill is 20 subjected upon reversal of the hammer piston at the ends of its stroke in the hammer motor cylinder, that is, to effect feeding of the drill by means controlled automatically by the vibrative action set up within the drill during the drilling 25 operation. The improved automatic feeding mechanism 1 comprises a supporting frame 9 secured, as by bolts 10, to a transverse plate 11 suitably secured to the upstanding frames of the guide frame or tower 4. Herein formed integral 30 with the frame 9 are projecting brackets 12, 12 having detachable caps 13, and which support the extremities of a horizontal shaft 14, this shaft being secured against rotative movement 35 with respect to the brackets by means of usual keys 15.

Journaled on bearing sleeves 16 supported by the shaft 14, and arranged between the brackets 12, 12, is a cable winding drum 17 having wound thereon or snubbed thereabout a feeding cable 40 18. This cable has a portion 19 extending upwardly from the drum 17 and passing around a guide sheave 20 journaled at the upper end of the guiding frame or tower, and the free end of this cable portion extends downwardly into connection at 21 to the guide frame 6 of the rock drill. The cable portion 22 extends downwardly from the drum 17 about a guide sheave 23 journaled at the lower end of the guiding frame, and the free end of this cable portion extends upwardly into connection, at 24, with the rock drill 45 guide frame 6. The connections 21 and 24 with the rock drill guide frame may be made adjustable, as by threaded screw and nut connections or the like, so that the cable portions may be 50 55

5 maintained at the desired tautness. In order to counterbalance the weight of the rock drill, there is provided a counterbalance weight 25 guided on the guide frame or tower at the opposite side thereof from the drill and connected, as by clamps or otherwise, to the portion 19 of the feed cable.

10 Associated with the cable-engaging feeding drum 17 is the improved recoil resistance means, herein in the form of a reversible intermittent grip device, generally designated 26. This intermittent grip device is herein in the form of a reversible roller gripping means comprising a roller carrier 27 keyed at 28 to the shaft 14 and arranged in a chamber 29 formed within the drum flange 30. This roller carrier 27 is provided with inclined surfaces 31 with which there are engageable one set of gripping rollers 32 normally urged towards their gripping position by 15 coiled springs 33. Engageable with opposingly inclined surfaces 34 on the roller carrier 27 is a set of reversing rollers 35, normally urged towards gripping position by coiled springs 36. The carrier 27 is provided with lateral arms 37 having recesses 38 which receive and position the inner ends of the coiled springs. Rotatably mounted at 39 on the shaft 14 and forming a closure for the outer side of the chamber 29, is a rotatable reversing plate 40 having a suitable 20 operating handle 41. This plate 40 is provided with arm-like projections 42 which extend in the space 43 between the carrier 27 and the inner surface 44 of the drum flange 30 and between the rollers 32 and 35, in the manner shown in Fig. 3. 25 This reversing plate has formed therein a bore 45 in which is guided a spring pressed locking plunger or latch 46 engageable with notches 47 formed in the shaft 14. This plunger is normally held in its locking position by a coiled 30 spring 48 and is provided with a release stem 49 connected at 50 to a release lever 51 pivotally mounted within the grip portion of the handle 41.

When the roller reverse plate 40 is in the position shown in Fig. 2, with the projections 42 in 45 their intermediate position, the gripping rollers are held in wedging engagement with the inclined surfaces 31, 34 by their coiled springs, thereby causing a gripping engagement with the inner periphery of the drum flange 30. When 50 the roller reverse plate is rotated in one direction, the projections 42 engage one set of the rollers, releasing the same, so that the other set of rollers acts to control rotation of the drum in one direction. When the reverse plate 40 is moved 55 into its reverse position, the other set of rollers is released, thereby to effect control of drum rotation in the opposite direction.

During certain stages in the operation of devices of this character it is at times desirable that 60 the movement of the drill relative to its guide frame may be to some extent retarded or checked. This is particularly the case when first starting a drill hole, and also whenever soft rock is encountered during drilling, thereby to prevent too 65 rapid penetration of the soft rock by the drill steel. In order, therefore, to insure against a too rapid feeding movement of the drill, there is provided on the drum flange 30 an external braking surface 53 with which there is engage- 70 able a brake band 54. One end of this brake band is secured at 55 to a lug 56 formed integral with the drum supporting frame 9, while the other end of the brake band is connected at 57 to an eye-bolt 58. This eye-bolt passes through an 75 opening 59 formed in the lug 56 and is threadedly

engaged by an adjusting nut 60 having an operating handle 61. When the nut 60 is rotated by the handle 61, the eye-bolt may be moved axially in one direction or the other, thereby to tighten or loosen the brake band as desired.

5 The operation of the improved feeding mechanism will be clearly apparent from the description given. Let it be assumed that pressure fluid is being supplied to the hammer motor and that the hammer piston is reciprocating to deliver 10 impact blows to the drill steel 8, and that the hammer piston causes a vibrative action to be set up within the drill so that longitudinal jars or shocks are imparted to the drill guide frame 6. The operator then releases the locking latch 15 and grasps the handle 41 to rotate the reverse plate into forward feeding position, thereby releasing one set of the gripping rollers. The other set of gripping rollers controls drum rotation, so that as the shocks or jars set up within 20 the drill are transmitted to the drum through the portion 19 of the feeding cable, the drum is permitted to rotate in only a forward feeding direction, the gripping rollers holding the drum against rotative movement in the opposite direction; and as a result, the drill will be gradually advanced towards the work in accordance with the degree of penetration of the drill steel 25 into the work.

When it is desired to effect feed of the drill 30 upwardly along the guiding frame, the operator grasps the handle 41 and rotates the reverse plate 40 into its opposite or reversing position, thereby releasing the forward feed rollers and rendering the reverse feed rollers operative. The vibrative 35 action set up within the drill is then transmitted, through the cable portion 22, to the drum, and as the roller gripping device permits rotation of the drum only in the reverse feeding direction, the drill is gradually fed upwardly along the guide- 40 way.

If during the operation of the drilling mechanism it may be found desirable to retard the movement of the drill relative to its guiding frame the brake 54 may be applied to retard the rotation 45 of the drum, and as a result progress of the drill along its guided frame is retarded or checked.

It will be evident that by adjusting the connections 21 and 24 of the cable with the drill, more or less slack may be placed in the cable portions, 50 thereby to lessen the vibrative action thereon by the drill, and as a result the feed may thereby be varied. The counterbalancing weight 25, of course, facilitates upward feeding of the drill along its guide.

55 As a result of this invention, it will be noted that an improved rock drill feeding mechanism is provided which is entirely automatic so that the drill is fed automatically in accordance with the degree of penetration of the drill steel into the 60 work. It will further be noted that an improved rock drill feeding mechanism is provided which is controlled automatically by the vibrative action set up within the drill during the drilling operation and having associated therewith improved 65 control means whereby the feed may be regulated as desired. These and other advantages and uses of the invention will be clearly apparent to those skilled in the art.

70 While there is specifically described in this application one form which the invention may assume in practice, it will be understood that this form is shown for purposes of illustration only, and that the invention may be modified and embodied in various other forms without departing 75

from its spirit or the scope of the appended claims.

What I claim as new and desire to secure by Letters Patent is:

- 5 1. In a rock drilling mechanism, the combination with a hammer rock drill and a guiding frame on which the rock drill is slidably guided, of feeding means for the drill controlled automatically by the vibratory action set up within the drill during the drilling operation, comprising a cable secured at its opposite ends to the drill, pulleys at the opposite ends of the guiding frame for guiding the cable, a snubbing drum journaled on said guiding frame and about which the intermediate portion of the cable extending between said guide pulleys is wound, and intermittent gripping means for controlling the direction of drum rotation and reversible at will to control drum rotation in either of opposite directions to effect drill feed in either of opposite directions along said guiding frame.
- 10
- 15
- 20

2. In a rock drilling mechanism, the combination with a hammer rock drill and a guiding frame on which the rock drill is slidably guided, of feeding means for the drill controlled automatically by the vibratory action set up within the drill during the drilling operation, comprising a cable secured at its opposite ends to the drill, pulleys at the opposite ends of the guiding frame for guiding the cable, a snubbing drum journaled on said guiding frame and about which the intermediate portion of the cable extending between said guide pulleys is wound, intermittent gripping means for controlling the direction of drum rotation and reversible at will to control drum rotation in either of opposite directions to effect drill feed in either of opposite directions along said guiding frame, and drum braking means for controlling drum rotation to vary the rate of drill feed.

JOHN L. REILLY. 20
